US00D843402S

(12) United States Design Patent (10) Patent No.: US D843,402 S
Casse et al. (45) Date of Patent: * Mar. 19, 2019

(54) DISPLAY SCREEN OR PORTION THEREOF WITH GRAPHICAL USER INTERFACE

(71) Applicant: Fisher & Paykel Healthcare Limited, Auckland (NZ)

(72) Inventors: Benjamin Wilson Casse, Auckland (NZ); Christopher Harding Campbell, Auckland (NZ); Katarzyna Sobolewska, Auckland (NZ); David Robert Keith Walker, Auckland (NZ)

(73) Assignee: Fisher & Paykel Healthcare Limited, Auckland (NZ)

() Term: 15 Years

(21) Appl. No.: 29/600,203

(22) Filed: Apr. 10, 2017

(51) LOC (11) Cl. 14-04

(52) U.S. Cl.

USPC D14/486

(58) Field of Classification Search

USPC D14/485-495

(57) CLAIM

The ornamental design for a display screen or portion thereof with graphical user interface, as shown and described.

DESCRIPTION

The FIGURE is a front view of a display screen or portion thereof with a graphical user interface showing our new design.

The broken lines, including those showing a display screen or portion thereof and those depicting portions of a graphical user interface, form no part of the claimed design.
